(57) **CLAIM**

The ornamental design for a fishing rod grip accessory, as shown and described.

DESCRIPTION

FIG. 1 is a first perspective side view of the design; FIG. 2 is second perspective side view of the design; FIG. 3 is a direct side-on view of the design; FIG. 4 is an end-on view of the design, viewing from a first end; and, FIG. 5 is an end-on view of the design, viewing from a second end, which is identical in design to the first end. The broken lines depict portions of the fishing rod grip accessory that form no part of the claimed design.
